DESIGN FOR A UTILITY WAGON

Adolph H. Wende, St. Louis, Mo., assignor to Henry Kleinkauf, Omaha, Nebr., Emil Haas and Henry Gould, both of Kansas City, Mo., Alfred Natkin, Houston, Tex., Bertram M. Natkin, Clayton, Mo., and Samuel J. Shure, St. Louis, Mo., doing business as Natkin & Company, Brentwood, Mo.

Application April 24, 1948, Serial No. 145,940

Term of patent 14 years

(Cl. D14—3(4))

To all whom it may concern:

Be it known that I, Adolph H. Wende, a citizen of the United States, residing at the city of St. Louis, State of Missouri, have invented a new, original, and ornamental Design for a Utility Wagon, of which the following is a specification, reference being made to the accompanying drawings, forming a part thereof, in which Figure 1 is a perspective view of a utility wagon embodying my new design with the door thereof shown in closed position; Figure 2 is a perspective view thereof with the door shown in opened position; Figure 3 is a top plan view thereof; and Figure 4 is a side elevational view thereof.

I claim:

The ornamental design for a utility wagon, substantially as shown.

ADOLPH H. WENDE.
